UNITED STATES PATENT OFFICE.

JAMES E. MEAGHER, OF BURLINGTON, VERMONT.

BALL-COCK.

No. 874,523.

Specification of Letters Patent.

Patented Dec. 24, 1907.

Application filed July 26, 1906. Serial No. 327,872.

To all whom it may concern:

Be it known that I, JAMES E. MEAGHER, a citizen of the United States, residing at Burlington, in the county of Chittenden and 5 State of Vermont, have invented a new and useful Improvement in a Ball-Cock, of which the following is a specification.

This invention relates to ball cocks and more particularly to ball cocks for flush 10 tanks, the object being to provide a valve which is very simple and cheap in construction and one which is noiseless in operation.

Another object of my invention is to provide a valve with a reversible seat so that it 15 can be readily reversed when one has become worn out and one which can be readily replaced by a new one when desired.

Another object of my invention is to provide a strainer in connection with the valve 20 so that the valves are protected from the chips, scales, gravel and sand which cause the valves to leak and at the same time serving the purpose of making the valves noiseless.

25 A still further object of my invention is to provide the valves with an ordinary rubber or leather washer which can be readily replaced when desired without the use of tools.

30 A further object of my invention is to provide the arm carrying the float with a roller adapted to bear against the arm carrying a valve cap—so that all noises and friction is prevented.

With these various objects in view, the 35 invention consists in the novel features of construction, hereinafter fully described and pointed out in the claims.

In the drawings forming a part of this specification:—Figure 1 is a section through 40 a tank showing my improved flush valve in place. Fig. 2 is a top plan view of the same showing the tank partly broken away. Fig. 3 is a side view of the flush valve showing it provided with a modified head carrying 45 the float rod. Fig. 4 is a vertical sectional view through the valve and tank. Fig. 5 is a section taken on line 5—5 of Fig. 4 the valve seat being removed. Fig. 6 is a perspective view of the collar provided with the 50 supporting arms. Fig. 7 is a perspective view of the enlarged end of the pipe section. Fig. 8 is a perspective view of the arm carrying the cap valve provided with the washer. Fig. 9 is a perspective view of the head carrying 55 the float rod. Fig. 10 is a perspective

view of the reversible seat. Fig. 11 is a perspective view of the washer. Fig. 12 is a perspective view of my improved strainer.

Referring to the drawing A indicates an ordinary tank provided with an opening in 60 its bottom adjacent one end in which is arranged a pipe section B provided with an enlarged end forming a shoulder on which is arranged a rubber washer C resting against the bottom. The other end of the pipe is 65 threaded, carrying a rubber washer C', and a nut C'', which is adapted to clamp the pipe therein so as to form a water tight joint. A supply pipe C'', is adapted to be connected to the end of the pipe section in the ordinary 70 manner. The enlarged end of the pipe B is provided with bores of two diameters, the larger bore being internally threaded. A series of perforated disks D forming a strainer provided with oppositely disposed arms D' 75 having angled ends, is seated on the shoulder formed by the smaller bore, the angled ends of the arm resting on the shoulder formed by the larger bore so that the strainer can be easily taken out when desired. A pipe E, 80 having rounded ends to form valve seats and a central flange E', having threads formed on its edge, is adapted to be secured into the larger bore so as to form a reversible valve seat which can be easily replaced by a new 85 one when desired.

Mounted on the enlarged end of the pipe B is a collar F having opposite disposed upwardly extending arms F', F'', having bifurcated ends, the walls of which are apertured. 90 The arm F' extends upwardly at an angle and the arm F'' extends up vertically above the arm F', and the bifurcation formed therein is greater than the arm F'. Pivoted between the bifurcation in the arm F', on a pin G', is the reduced apertured end of an arm G, which is provided with a flattened free end. Secured to the arm G midway of its length is a valve cap H provided with a central depression forming a recess in which is mounted 95 a rubber or leather washer I, adapted to bear against the end of the pipe E and completely close the same.

Mounted in the bifurcated arm F'', on a pin J', is a lever J provided with a fork J'', in 105 which is mounted a roller J'', adapted to bear against the flattened end of the arm G and close the valve. A curved arm J', projects downwardly from the lever adapted to engage the under side of the flattened end of the 110

arm G and open the valve. The lever J is provided with a socket in which a rod K is secured provided with a float K' at its end.

In Fig. 3 I have shown a lever L provided with spaced arms L' between which the flattened end of the arm is adapted to fit for opening and closing the valve.

From the foregoing description it will be readily seen that I have provided a very effective valve which is not apt to get out of order and one which can be very easily repaired if necessary as the parts can be readily replaced by new ones.

Having thus fully described my invention, what I claim as new and desire to secure by Letters Patent is:-

The combination with a tank provided with an opening in its bottom, of a pipe secured in said opening provided with an enlarged end having bores of two diameters, one of said bores being threaded, a pipe provided with a threaded central flange adapted to be screwed into said threaded bore, a perforated disk seated on the shoulder formed by the small bore, provided with oppositely disposed upwardly extending arms having

angled ends adapted to rest on the shoulders formed by the threaded bore under the flange of the pipe, a collar mounted on said pipe under the enlarged head, provided with oppositely disposed upwardly extending bifurcated arms of different lengths, the walls of which are apertured, an arm pivotally mounted between the bifurcation of the shorter arm provided with a cap forming a valve adapted to fit over the end of the pipe secured in the head, the end of said bar being flattened at its free end, a lever mounted in the bifurcation of the longer arm provided with a fork carrying a roller adapted to engage the top of the flattened end of said bar, a curved arm projecting downwardly from said lever, adapted to engage the under side of the flattened end of the arm, a rod secured in said head carrying a float, and means for securing said pipe in said tank, for the purpose described.

JAMES E. MEAGHER.
